NECKTIE DISPLAY RACK OR SIMILAR ARTICLE

Morris Aron, South Norwalk, Conn.

Application November 2, 1949, Serial No. 5,834

Term of patent 14 years

(Cl. D80—9)

To all whom it may concern:

Be it known that I, Morris Aron, a citizen of the United States and a resident of South Norwalk, Connecticut, whose post-office address is 10 East 34th Street, New York 16, N. Y., have invented a new, original, and ornamental design for Necktie Display Rack or Similar Article, of which the following is a specification, reference being had to the accompanying drawing, forming a part hereof, in which

Figure 1 is a perspective view of a necktie display rack, or similar article, showing my new design; and

I claim:

The ornamental design for a necktie display rack or similar article, as shown.

MORRIS ARON.
